UNITED STATES PATENT OFFICE.

KARL L. TOELCKE, AATE MIKKOLA, AND LEON SHAPIRO, OF CHICAGO, ILLINOIS.

CLASP FOR BRACELETS.

Original application filed October 9, 1922, Serial No. 593,455. Divided and this application filed January 11, 1923. Serial No. 612,103.

To all whom it may concern:

Be it known that we, KARL L. TOELCKE, AATE MIKKOLA, and LEON SHAPIRO, all citizens of the United States, and residents of Chicago, in the county of Cook and State of Illinois, have invented a new and useful Improvement in Clasps for Bracelets, of which the following is a full, clear, and exact description.

10 Our invention relates to improvements in clasps for bracelets, and it consists in the combinations, constructions, and arrangements herein described and claimed.

An object of our invention is to provide a 15 clasp for a bracelet or the like that securely locks the free ends of the bracelet against unintentional separation from one another.

A further object of our invention is to provide a device of the character described 20 that is constructed in such a manner as to resemble the ordinary bracelet link, and therefore not contrasted against the general design and appearance of the bracelet.

A further object of our invention is to 25 provide a novel means for releasing the lock, which means is not likely to become accidentally actuated.

A further object of our invention is to 30 provide a device of the character described that is extremely durable, and which is thoroughly practical commercially.

Other objects and advantages will appear 35 in the following specification, and the novel features of the invention will be particularly pointed out in the appended claim.

Our invention is illustrated in the accompanying drawings, forming part of this application, in which—

Figure 1 is a side elevation of an embodiment of our invention,

Figure 2 is a sectional view of the mechanism illustrated in Figure 1 slightly enlarged, and

Figure 3 is a view, partly in section, along the line 3—3 of Figure 2.

In carrying out our invention, we make use of a bracelet constructed of a plurality of links 1 which are provided with a certain ornamental design constructed at 3 on the upper face 2 thereof. In the case shown in Figure 1, the ornamentation 3 consists in a setting for a jewel. The links 1 are connected to one another in any well known manner, but we choose to make use of the novel connecting means disclosed in our co-pending application for patent on bracelet, Serial No.

593,455, our present application being a division of the said co-pending application.

Our novel locking means is constructed of a casing 4 having the general appearance of two of the adjacent links 1. This casing 4 is provided with a pair of ornamentations 3 for setting jewels or the like, precisely as in the case of the links 1, and therefore has substantially the same outward appearance of the links. The casing 4 is provided on its interior with a pivotally mounted latch member 5 (see Figures 2 and 3). This latch member or lever is constantly pressed downwardly by means of a compression spring 6 held against lateral movement by a pin 7 inserted in the top wall 8 of the casing 4. The outer end 9 of the latch lever 5 falls short of the adjacent end wall 10 of the casing.

75 A plate 11 is secured to the bottom of the casing 4, thereby closing all but the forward end 12 of the casing.

A clasp member 13 is secured to the opposite end of the bracelet and has substantially the same outward appearance as the links 1 (see Figure 1). The clasp member 13, however, is provided with an outwardly extending tongue 14, which tongue is formed with a latch tooth 15 adjacent its outer end on the upper surface thereof.

80 This tongue 14 is so constructed that when it is inserted through the open end 12 of the casing 4, it will engage with the spring 90 pressed latch lever 5 and be held from withdrawal from the casing until the lever 5 is moved against action of the spring 7.

The means for moving the latch lever 5 out of engagement with the tongue 14 is clearly shown in Figure 3 and consists in a diminutive bell crank 16 pivotally mounted at 17 to a side wall of the casing 4. The bell crank 16 is provided with a finger grip 18 and a work engaging portion 19. The portion 19 is inclined and is normally in contact with an inclined portion 20 provided in the side wall of the latch lever 5.

100 It will be evident therefore that when the bell crank 16 is moved to the position shown in dotted lines that the latch lever 5 will be elevated and thereby moved out of engagement with the tongue 14 so that the tongue may be removed and the clasp opened to release the bracelet from the wrist of the wearer.

110 From the foregoing description of the various parts of the device, the operation

thereof may be readily understood. The operation of our improved clasp is extremely simple. To engage the two locking members, it is merely necessary to project the 5 tongue 14 through the open end 12 of the casing 10 and press these members toward one another. As shown in Figure 2, the tongue 14 will engage with the spring 10 pressed lever 5 in such a manner as to prevent the unintentional withdrawal of the tongue 14.

In order to release the tongue 14 from engagement with the latch lever 5, it is necessary to manually move the bell crank 16 and 15 therefore actuate the latch lever 5 so that it will move above the top portion of the latch tooth 15 on the tongue 14 and permit withdrawal of the tongue and the subsequent separation of the clasp members.

20 We claim:

A clasp for a bracelet consisting of a casing having substantially the same configura-

tion as the links of said bracelet, and having one end thereof open, said clasp member being adapted to be secured to one of the free 25 ends of said bracelet, a spring pressed latch lever disposed within said casing, a bell crank secured to said casing and having engagement with said latch lever, whereby said latch lever may be actuated at will, a second 30 latch member arranged to be secured to the opposite free end of said bracelet, said second named clasp member being provided with a tongue having a latch tooth at the outer end thereof and adapted to enter said 35 casing through the open end thereof and to engage with said latch lever, whereby said clasp members may be secure from unintentional separation.
